SHEET METAL CONTAINER

Herbert Schrader, Wheeling, W. Va., assignor to
 Continental Can Company, Inc., New York,
 N. Y., a corporation of New York

Application May 8, 1942, Serial No. 442,335

2 Claims. (Cl. 220—81)

The invention relates to new and useful improvements in a sheet metal container and more particularly to a sheet metal container of the type shown and described in patents, Nos. 2,171,711 and 2,171,714 granted to Walter G. Plumb et al. and Herbert Schrader, respectively, on September 5, 1939.

An object of the invention is to provide a construction of side seam wherein the metal parts of the side seam in the region of the lap sections will be pressed into intimate contact with a thermoplastic sealing material when the closure ends are secured to the container body by double seaming.

A further object of the invention is to provide a lock and lap side seam wherein one of the hooks of the lock section is extended to the end of the side seam and becomes a part of the lap section.

A further object of the invention is to provide a side seam of the above type which is rendered hermetically tight by a thermoplastic sealing material which extends throughout the limits of the side seam, which sealing material is of such a character as to remain pliable and operates to close any leaks formed in the lap sections during the flanging or double seaming of the ends thereof.

These and other objects will in part be obvious and will in part be hereinafter more fully described.

In the drawing which shows by way of illustration one embodiment of the invention,

Figure 1 is a plan view of a body blank which has been notched and provided with hooks preparatory to the forming of a container body;

Figure 2 is an edge view of the body blank shown in Figure 1;

Figure 3 is a view of a portion of the container body in the region of the side seam after the seam has been bumped and the body in the region of the seam preflanged, said view being taken from the outside of the container body;

Figure 4 is a section view on the line 4—4 of Figure 3;

Figure 5 is a sectional view of the line 5—5 of Figure 3;

Figure 6 is an inside view of a portion of the container body shown in Figure 3;

Figure 7 is a vertical sectional view through the side seam of the container body after the container body is bumped and preflanged;

Figure 8 is a vertical sectional view through a portion of the side seam after the container body has been flanged;

Figure 9 is a vertical sectional view through a portion of the side seam after the end closure has been double seamed thereto;

Figure 10 is a view showing one way of applying the thermoplastic sealing material to both the inner and outer faces of the inside hook of the body blank;

The invention is directed to a container of sheet metal and of the type wherein the body is usually referred to as a solderless side seam container body. The side seam includes interlocking hooks and lap sections. The inside hook is extended to the full length of the side seam so that said hook extends out into the flange and is rolled into the double seam joining an end closure to the body of the container. The outside hook terminates at the lower side of the double seam which secures the end closure to the body. During the bumping operation the lap section at the end of the outside hook is pressed against the portion of the inside hook which extends throughout the lap section and in turn presses said hook tightly against the body wall carrying the same. This forms three walls in the lap section of the seam which are very tightly brought into contact with each other not only during the bumping operation, but during the double seaming operation which joins the ends of the container body.

Referring more in detail to the drawing, the body blank is indicated at 1. This body blank is cut along an inclined line 2 at one end thereof which is usually referred to as a notching operation. The blank is folded back upon itself at this notched end to form a hook 3 which is usually referred to as the outside hook. The other end of the body blank is not cut but is folded back upon itself to form a hook 4 which extends from one side of the blank to the other and in the finished side seam this hook extends all the way from one end of the side seam to the other end thereof.

After the body blank has been made up in the manner just described, this inside hook 4 is presented to a coating roll 5 rotating in a bath of coating material so as to carry a layer of the coating material. The hook is so presented to the coating roll that the thermoplastic sealing material carried by the roll will coat the hook on both sides thereof. If found desirable, the outside hook 3 may be coated on the outside or on both sides with a thermoplastic sealing material.

The thermoplastic sealing material is of such a character that it remains pliable even after the

side seam is completed and the can body flanged and until the closure end is double seamed to the container body, even though the closure member is not immediately secured to the body.

The can body blank, after it is formed with the hooks and the sealing material is applied thereto, is formed around a horn into body shape and the hooks interlocked in the usual way. The side seam is then bumped. The bumping horn is preferably so constructed that the interlocked hook parts of the side seam will be brought into intimate contact with each other as shown in Figure 5. Either the bumping iron or the anvil horn on which the seam is bumped is preferably provided with projections which form indentations 6. The interlocked hook portions of the side seam are indicated at 7 in Figure 5. Along one side of the interlocked portions the body wall is bent inward, as indicated at 8, and along the other side of the hook portion of the side seam the body wall is provided with an outwardly extending bead 9 which places the metal 10 of the bead closely around the base of the outside hook while the portion 8 of the body wall extends closely around the base of the inside hook. This draws the metal parts into very close intimate contact and causes the sealing material extending throughout the limits of the locked section to fill all the spaces and make a very efficient hermetically sealed side seam section. This side seam, by the curving of the metal, is offset outwardly from the body wall. The shaping of the body wall and the offsetting of the seam outwardly holds the hooks firmly interlocked and prevents any collapsing of the side seam due to external pressure applied to the body wall.

The inside hook, as noted above, extends from one end of the side seam to the other end thereof and the portion 4a of the inside hook will be bumped tightly against the body wall. The section 11 of the body wall extending beyond the outside hook overlaps the inside hook portion 4a as shown in Figure 4 and during the bumping operation the bumping iron will contact with this section 11 forcing the same against the hook portion 4a and bringing said hook portion into tight engagement with the body wall.

As noted above, the inside hook 4 has coating material applied to both the inner and outer faces thereof and therefore there will be coating material between the hook section 4a and the body wall carrying the same and between the hook section 4a and the body wall 11 overlapping the same. This pressing of the body wall 11 and the hook portion 4a against the body wall carrying the hook portion will close the inner hook closely around the end of the outside hook 3 as indicated at 12 in Figure 7. This fills the space joining the hook section of the side seam with the lap section of the side seam and makes a very tight hermetic seal for the side seam, not only in the hook section but in the lap section.

During this bumping operation of the side seam the portion of the end of the container body which is to be formed into a flange is bent radially outward for what is referred to as a pre-flanging operation. In other words, theselapping sections in the region of the side seam are bent outwardly by a bumping operation which leaves them in tight contact because they are gripped between the anvil and the bumping iron during this preflanging operation. The bead 9 is formed during the bumping operation as above noted and this bead vanishes in the portion of the body wall which is to be flanged. This bead

takes up the stretch in the metal when the can body is preflanged, the side seam is not opened up as the bead supplies enough extra metal to take care of what is required for the flange.

After the can body has been bumped and preflanged in the manner described above, it is then subjected to a flanging die which will roll the edge portion of the body wall outward into a flange, as indicated at 13 in Figure 8. During this flanging operation the lap sections and the side seam, due to the initial shaping of the parts by the preflanging operation, will be carried out into the finished flange without breaking the seal between the lap sections. Here again the bead along the side seam which extends well out into the region which is flanged gives up slack to the forming of the flange and prevents lateral straining on the lap sections of the side seam.

After the flange has been formed on the can body as shown in Figure 8, an end closure 14 is secured to the body by double seaming. This end closure has the usual depression providing a vertical wall 15 in which depression the chuck of the seaming mechanism is placed. The flange 16 of the closure member 14 is rolled with the flange 13 into a double seam in the usual manner. This rolling of the parts into a double seam as shown in Figure 9 will press the outer lap section of the side seam against the extended portion of the inside hook and force the inside hook against the body wall carrying the same. It will also draw the inside hook tightly around the end of the outside hook and thus make a very tight seal, not only in the lap sections, but in that portion of the side seam where the lap sections join the interlocked hook sections. As noted above, the sealing composition is preferably of the thermoplastic type and is of such a character that it remains pliable so that the end closure, whenever it is secured to the container body, will aid in making a very tight side seam extending all the way into the double seam.

It is obvious that many changes may be made in the details of construction of the solderless side seam sheet metal container described above without departing from the spirit of the invention as set forth in the appended claims.

I claim:

1. A sheet metal container comprising a body blank having its edge portions joined by a solderless side seam including an inner hook extending the full length of the side seam and an outer hook terminating short of the ends of the side seam, said hooks being interlocked throughout the length of the outer hook, the end portions of the inner hook being bent into contact with the body wall beyond the ends of the outer hook and lapped by the body wall carrying the outer hook and a plastic sealing composition covering the inner and outer faces of said inner hook and extending throughout the length of the lock and lap sections of the side seam for hermetically sealing the same.

2. A sheet metal container comprising a body blank having its edge portions joined by a solderless side seam including an inner hook extending the full length of the side seam and an outer hook terminating short of the ends of the side seam, said hooks being interlocked throughout the length of the outer hook, the end portions of the inner hook being bent into contact with the body wall beyond the ends of the outer hook and lapped by the body wall carrying the outer hook and a plastic sealing composition covering the inner and outer faces of said inner

hook and extending throughout the length of the lock and lap sections of the side seam for hermetically sealing the same, an end closure member double seamed to one end of said container body, said inner hook being extended into said double seam and said outer hook terminating at

the lower edge of the double seam whereby a forming of the double seam will press the parts of the side seam beyond the end of the outer hook into intimate contact with each other and the plastic sealing material therebetween.

5 HERBERT SCHRADER.
